UNITED STATES PATENT OFFICE.

ARTHUR J. BAZELEY, OF CLEVELAND, OHIO, ASSIGNOR TO THE NATIONAL MALLEABLE CASTINGS COMPANY, OF CLEVELAND, OHIO, A CORPORATION OF OHIO.

UNCOUPLING MECHANISM FOR CARS.

1,090,591.

Specification of Letters Patent.

Patented Mar. 17, 1914.

Original application filed May 9, 1910, Serial No. 560,127. Divided and this application filed September 14, 1911. Serial No. 649,336.

To all whom it may concern:

Be it known that I, ARTHUR J. BAZELEY, a resident of Cleveland, in the county of Cuyahoga and State of Ohio, have invented 5 a new and useful Improvement in Uncoupling Mechanisms for Cars, of which the following is a full, clear, and exact description, reference being had to the accompanying drawings, forming part of this specification, 10 in which—

Figure 1 is a side view of a coupler partly broken away and showing the application of my invention thereto; Fig. 2 is an end view of the coupler and uncoupling mechanism 15 shown in Fig. 1.

The present application is a division of my pending application, Serial No. 560,127, filed May 9, 1910.

The invention has relation to uncoupling 20 mechanism for railway cars, and is designed to provide means of simple and efficient character for operating the lock-lifting and knuckle-throwing elements of a bottom-operating coupler.

25 The nature of my invention will be best understood by reference to the drawings which will now be described, it being premised, however, that various changes may be made in the details of construction and arrangement of the parts by those skilled in the art, without departing from the spirit and scope of my invention, as defined in the claim.

In these drawings, the numeral 2 designates the end sill of the car, and 3 a coupler head having the usual pivoted knuckle 4.

5 is a lever for operating the lock-lifting and knuckle-throwing elements of the coupler, and is preferably of the character more 40 fully described and claimed in my pending application, Serial No. 539,258, filed January 21, 1910. This lever is pivoted at 6 to lugs 7, depending from the bottom of the coupler, and extends longitudinally and rearwardly 45 below the coupler head, its rear end terminating in an upwardly extending finger or pusher portion 8, which is arranged to engage and operate the lock-lifting and knuckle-throwing elements of the coupler, as

more fully described in said application. 50 This lever is prevented from falling below its normal position by means of the lug or projection 9, thereon, which engages the coöperating lug or projection 10 on one of the lugs 7. 55

The numeral 11 designates an actuating member having a hooked end portion 12, which pivotally engages an eye 13, depending from the under side of the coupler head. This actuating member extends transversely 60 underneath the head through an eye 5^a of the lever 5, and its free end is connected by suitable means, such as the link and clevis 14, with an uncoupling rod 15, which is supported in suitable bearings (not shown) on 65 the end sill of the car. The rotation of the uncoupling rod 15 pulls on the link and clevis 14, thereby lifting the actuating member 11 and raising the lever 5, to operate the lock-lifting and knuckle-throwing elements 70 16.

The invention provides means of simple and efficient character for operating the lock-lifting and knuckle-throwing elements of a bottom-operating coupler from the side of 75 the car.

I claim:

In a car coupler of the M. C. B. type, a knuckle pivotally connected to said coupler by means of pivot ears, lugs connected to 80 one of said pivot ears, an arm pivoted to said lugs and extending rearwardly and longitudinally of said coupler, said arm having an eye therein intermediate its ends and being adapted to operate the coupler lock, a 85 lever pivoted to the guard arm of said coupler and extending transversely of said coupler and through the eye of said arm, said lever being arranged so as to always act against the upper side of said eye, and means 90 to move said lever so as to revolve said arm about its pivot to unlock the coupler.

In testimony whereof, I have hereunto set my hand.

ARTHUR J. BAZELEY.
